(57) CLAIM

The ornamental design for a pacifier handle, as shown and described.

DESCRIPTION

FIG. 1 is a top perspective view of a pacifier handle showing my new design;

FIG. 2 is top plan view thereof;

FIG. 3 is a bottom plan view thereof;

FIG. 4 is a front side elevational view thereof;

FIG. 5 is a rear side elevational view thereof;

FIG. 6 is a left side elevational view thereof; and,

FIG. 7 is a right side elevational view thereof.

The broken lines depict portions of the pacifier that form no part of the claimed design.
